CLAIM

The ornamental design for an adjustable lap desk as shown and described.

DESCRIPTION

FIG. 1 is a front, right and bottom perspective view of an adjustable lap desk, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and bottom perspective view of the adjustable lap desk in a folded state.

The broken lines depict portions of the adjustable lap desk that form no part of the claimed design.
